UNITED STATES PATENT OFFICE.

LEROY S. PFOUTS, OF CANTON, OHIO, ASSIGNOR TO THE MILLER PASTEURIZING MACHINE COMPANY, OF CANTON, OHIO, A CORPORATION OF NEW JERSEY.

PASTEURIZER.

1,189,479.

Specification of Letters Patent.

Patented July 4, 1916.

Application filed November 20, 1911. Serial No. 661,339.

To all whom it may concern:

Be it known that I, LEROY S. PFOUTS, a citizen of the United States, residing at Canton in the county of Stark and State of Ohio, have invented certain new and useful Improvements in and relating to Pasteurizers, of which the following is a specification.

This invention relates to apparatus for the treatment of a liquid, such as milk.

The invention relates more particularly to a pasteurizing apparatus provided with mechanism in which the milk, after it is heated to the required temperature, is held at substantially that temperature for a predetermined or variable period of time before being cooled.

For the purpose of illustration, I have, in the accompanying drawing, shown and herein described one form of apparatus embodying my invention.

Figure 1 is a view of an apparatus for treating or pasteurizing a liquid, the holder being shown in section and parts of the heater and cooler being shown in elevation. Fig. 2 is a transverse section on the line 2—2 of Fig. 1. Fig. 3 is a top plan view of the top for the inner cylinder. Fig. 4 is a perspective view of the valve, valve stem and conduit. Fig. 5 is a sectional view on the line 5—5 of Fig. 2.

The apparatus consists of a heater 1, to which the liquid to be treated is fed from a suitable source of supply (not shown), a holder 2 which holds every portion or particle of the liquid after it has been heated, and a cooler 3 which receives the liquid from the holder and cools it to the desired degree. The heater 1, holder 2 and cooler 3 are preferably arranged with their inlet and outlets in different horizontal planes, so that the liquid will flow from one to the other substantially continuously under the influence of gravity after the complete operation of the apparatus is under way.

The heater 1 and cooler 3 may each be constructed in any ordinary or preferred manner. As the present invention relates to the holder 2, further description of the heater 1 and cooler 3 will not be necessary, although reference may be made to Letters Patent of the United States, No. 878,225, to John C. Miller, dated February 4, 1908, for a heater and cooler suitable for use

with the holder about to be described in detail.

Of the holder 2, 2^a indicates a casing or housing having a bottom 2^b and a cylinder 2^c forming the side wall or walls of the casing. Near its peripheral edge, the bottom 2^b is provided with a flange 2^d to which the lower end of the cylinder 2^c is connected.

2^e indicates an annular recess formed in the bottom 2^b adjacent the inner face of the flange 2^d and receives the lower end of the cylinder 2^c. This form of construction provides a liquid tight joint between the cylinder 2^c and bottom 2^b. The inner walls of the cylinder 2^c and bottom 2^b are preferably lined with some suitable non-corrodible material, for instance German silver, as indicated at 2^f, which does not affect the liquid being treated.

At its center, the bottom is preferably provided with an enlarged or reinforced portion 2^g, in which is formed an axial opening 2^h. Mounted in said opening 2^h is a liquid outlet member 2ⁱ formed with a conduit 2^j. This member extends upwardly from the bottom 2^b and is hollowed out to form a conically shaped seat for a rotary conical valve 2^k. The valve 2^k is formed with an axial conduit 2^l through it which serves as the conduit for the outlet member 2ⁱ when the valve is in normal position and during the pasteurizing operation 2^m, 2ⁿ, indicate openings formed respectively in the outlet member 2ⁱ and valve 2^k. These openings are arranged to register when the valve is rotated to one position and thus permit the liquid in the casing 2^a to flow into the outlet 2ⁱ and be removed from the casing at the end of the holding operation. This valve also permits the discharge of the cleansing fluid with which the inner walls of the casing may be cleaned from time to time. The outlet member is preferably provided with an integral flange 2° in which are formed openings 2^p. Extending through said openings are bolts or screws 2^q which secure the flange 2° to the thick portion 2^r of the casing bottom 2^b.

2^m indicates suitable devices for supporting the casing 2^a at the proper height relative to the heater 1.

2ⁿ indicates a cylinder concentrically arranged within the casing 2^a. It is provided with a bottom 2^r in which is formed a large

central opening 2ⁿ. The inner cylinder 2^m is of a size relative to the outer cylinder to leave an annular space 2^x between them. The exterior walls of cylinder 2^m are preferably provided with a series of longitudinally disposed ribs 2^{m'} which space the cylinder 2^m from the cylinder 2^c and also maintain it in concentricity with the latter.

2^o indicates a plurality of feet that are 10 adapted to support the bottom 2^a of the cylinder 2^m above the bottom 2^b of the casing 2^a to provide a space 2^{x'} between them.

2^p indicates a top, preferably of conical shape, carried by the cylinder 2^m. The peripheral edge of the top fits snugly within the cylinder 2^c and is formed with a series of openings 2^{p'} preferably V shape, through which the liquid passes to the conduit or space 2^x.

2° indicates a vessel or funnel arranged centrally of the top or plate 2^p. As shown in the drawings, the discharge nozzle 1^a of the heater leads to and discharges the heated liquid into the vessel 2^r. From the vessel

25 2^r the liquid flows onto the top 2^p through suitable outlet ducts 2^{p'x} found in the wall of the vessel 2^r adjacent to the upper surface of the top 2^p and is thus more or less uniformly spread out in all directions over

30 said top, from the outer peripheral edges of which it is discharged into the channels formed by the ribs 2^{m'}. From the channels between the ribs 2^{m'} it flows into the fluid space 2^{x'}, and from the latter space it enters the cylinder 2^m, through the opening 2^{n'}, and rises therein. The plate 2^p is preferably removable from the cylinder 2^m. It is provided with an annular rib on its under side, whereby it may be properly positioned

35 on the upper edge of said cylinder. 4 indicates a cover for the casing 2^a. It is provided with an annular depending rib 4^a which engages the inner wall of the cylinder 2^c and thus permits positioning and removal of the top 4 at will.

45 At 4^b, the cover 4 is formed with an opening through which the discharge nozzle 1^a for the heated liquid extends.

50 2^s indicates a conduit extending axially of the cylinders 2^c and 2^m. It is rigidly connected at its lower end to the valve 2^h. At its upper end, the conduit 2^s is open so as to permit the liquid, when it rises in the cylinder 2^m to the level of the open end of the conduit, to enter said end and flow down through it and the valve 2^h to the outlet member 2^g.

55 2^t indicates a spider or skeleton frame arranged within the cylinder 2^m and arranged to strengthen the sides of the inner cylinder. This frame also constitutes means for lifting the inner cylinder from within the outer one when desired.

60 2^v indicates a shaft extending through openings in the top 2^p and cover 4 and ro-

tatably mounted in a sleeve bearing carried by the top 2^p. At its lower end the shaft is rigidly connected to the upper end of the conduit 2^s by a ring member 2^v, or in any other suitable manner, without obstructing 70 the open end thereof. At its upper end the shaft is provided with a handle 2^{v'} which is preferably removable therefrom. As the shaft is rigidly connected to the conduit 2^s and the latter is fixed to the valve 2^g, the 75 latter may be opened and closed by the handle 2^{v'}, that is, rotated on the one hand so as to cut off communication directly with the outer cylinder 2^c through the valve to the outlet duct 2^{g'} and cause all of the material 80 to be treated to rise in the inner cylinder 2^m to the top of the conduit 2^s and flow down therethrough; and on the other hand the valve may be rotated so as to cause the openings in the valve and valve seat to register 85 and permit the discharge of the liquid directly from the outer cylinder through the valve and into the outlet duct.

5 indicates a pipe leading from the outlet member 2^g and connected thereto at its 90 upper end by a coupling 5^a.

5^b indicates a pipe connected with the lower end of the pipe 5 by a union 5^c. The pipe 5^b is provided with an up-take 5^d which carries a discharge nozzle 5^e at its upper 95 end.

3^a indicates a delivery pipe which extends into the lower portion of the cooler as shown in the drawings. At its upper end, this pipe carries a funnel 3^b which receives the 100 liquid from the discharge nozzle 5^e.

In the process of pasteurization of milk, or other liquid, wherein provision is made for holding the milk for a given length of time after it has been heated and before it is 105 cooled, various sorts of holding mechanisms have been utilized. With all of the earlier devices of this character of which I am aware, either a plurality of holding tanks have been employed or if a single tank has 110 been used, its construction in addition to the construction of the mechanism placed therein has been of such nature as not to lend itself to easy cleaning for sanitary purposes.

In my present invention, when the 115 connection between the heater conduit 1^a and the receiving vessel 2^r of the holder 2 is broken, the operating handle 2^{v'} for the valve 2^h is removed, the top 4 is detached and then the top 2^p, whereupon the valve 2^h and its stem or conduit member 2^s may be readily removed. Also by means of a suitable crane, or in any other desired way, the spider 2^t may be engaged and the inner cylinder 2^m lifted from within the outer cylinder 2^c, whereupon every part of the device 120 with which the material or liquid comes in contact will be readily accessible for cleaning purposes.

To those skilled in the art of making ap. 130

paratus of the class described, many alterations in construction and widely differing embodiments and applications of my invention will suggest themselves, without departing from the spirit and scope thereof. My disclosures and the description herein are purely illustrative, and are not intended to be in any sense limiting.

What I claim is:

16. 1. In apparatus of the class described, an outer cylinder, a bottom therefor having a passageway therethrough, a valve mechanism in said passageway, an inner cylinder having a top, the lower end of said cylinder being open and spaced from the bottom wall of the outer cylinder, a conduit serving as a valve stem and leading from the valves of said valve mechanism upwardly through said inner cylinder, means connected to said conduit for operating said valve, and means for introducing liquid to be treated between the inner and outer cylinders and at a point above the top of said conduit. 70
25. 2. In apparatus of the class described, an outer cylinder, a bottom therefor having a passageway therethrough, a valve mechanism in said passageway, an inner cylinder having a perforated bottom wall spaced from the bottom wall of the outer cylinder and removably mounted within the latter, a conduit serving as a valve stem and leading from the valve of said mechanism upwardly through said inner cylinder, means connected to said conduit for operating said valve, a removable cover for the inner cylinder, and means for introducing liquid to be treated between the inner and outer cylinders and at a point above the top of said conduit. 75
30. 3. In apparatus of the class described, the combination of an inner casing and an outer casing each provided with a top; the sides of the inner casing being spaced from the sides of the outer casing and the lower end of the inner casing being open to permit liquid to rise therein, and the bottom of the outer casing being formed with a passageway, a rotary valve mounted in said passageway, said valve being formed with a duct, a conduit connected with the duct of said valve and extending upwardly through said inner casing, the wall of the conduit being fixed to the wall of the valve, whereby the rotation of said conduit will operate said valve, an operating member connected to said conduit and extending through openings in the tops of said inner and outer casings, the walls of the passageway in the outer casing and of the openings in the tops of the casings serving to rotatively support said conduit and operating member, and means for discharging liquid between the said casings at a point above the upper end of said conduit. 80
40. 4. An apparatus of the class described, comprising an outer cylinder formed with an opening in its bottom, an inner cylinder open at its lower end to permit liquid to rise therein and separated from the outer cylinder to form a space between said cylinders, means for controlling the flow of the liquid upwardly in said inner cylinder or through the opening in the bottom of the outer cylinder, the said means comprising a conduit having an open upper end arranged within said inner cylinder and connected at its lower end with the opening in said outer cylinder and a valve mechanism at the lower end of said conduit arranged when open to permit the liquid to flow freely through the opening in the bottom of the outer cylinder, and means for discharging liquid between said cylinders. 85
45. 5. In apparatus of the class described, comprising a casing having a removable top and a bottom, said bottom being formed with a discharge opening, a cylinder having a removable top and a bottom, spacing devices interposed between the sides and bottom of said cylinder and said casing and arranged to form a fluid space between them, means for discharging material on the top of said cylinder whereby it flows over said top and down between the walls of the casing and cylinder, the said cylinder being formed with an opening in its bottom and permitting the material to rise therein, a conduit arranged within said cylinder, the lower end of said conduit being removably mounted in and communicating with said discharge opening in the bottom of the casing and its upper end being open and permitting the material to overflow into said conduit and be discharged, and a device fixed to said conduit and removably mounted in openings formed in the tops of said casing and cylinder and operating to support the upper end of said conduit. 90
50. 6. An apparatus of the class described, comprising a casing having a top and a bottom, said bottom being formed with a discharge opening, a cylinder having a top and a bottom, devices for supporting the bottom of the cylinder above the bottom of the casing to form a fluid space between them, ribs interposed between the side walls of the casing and cylinder and extending longitudinally from end to end thereof to form channels for the material, means for discharging material on the top of said cylinder whereby it flows over said top and down between the walls of the casing and cylinder, the lower end of said cylinder being open and permitting the material to rise therein, a conduit arranged within said cylinder, the lower end of said conduit being connected with said discharge opening in the bottom of the casing and its upper end being open and permitting the material to overflow into said conduit and be discharged, and a device connected to said conduit and removably sup- 95
60. 7. An apparatus of the class described, comprising an outer cylinder formed with an opening in its bottom, an inner cylinder open at its lower end to permit liquid to rise therein and separated from the outer cylinder to form a space between said cylinders, means for controlling the flow of the liquid upwardly in said inner cylinder or through the opening in the bottom of the outer cylinder, the said means comprising a conduit having an open upper end arranged within said inner cylinder and connected at its lower end with the opening in said outer cylinder and a valve mechanism at the lower end of said conduit arranged when open to permit the liquid to flow freely through the opening in the bottom of the outer cylinder, and means for discharging liquid between said cylinders. 100
65. 8. An apparatus of the class described, comprising an outer cylinder formed with an opening in its bottom, an inner cylinder open at its lower end to permit liquid to rise therein and separated from the outer cylinder to form a space between said cylinders, means for controlling the flow of the liquid upwardly in said inner cylinder or through the opening in the bottom of the outer cylinder, the said means comprising a conduit having an open upper end arranged within said inner cylinder and connected at its lower end with the opening in said outer cylinder and a valve mechanism at the lower end of said conduit arranged when open to permit the liquid to flow freely through the opening in the bottom of the outer cylinder, and means for discharging liquid between said cylinders. 105
70. 9. An apparatus of the class described, comprising an outer cylinder formed with an opening in its bottom, an inner cylinder open at its lower end to permit liquid to rise therein and separated from the outer cylinder to form a space between said cylinders, means for controlling the flow of the liquid upwardly in said inner cylinder or through the opening in the bottom of the outer cylinder, the said means comprising a conduit having an open upper end arranged within said inner cylinder and connected at its lower end with the opening in said outer cylinder and a valve mechanism at the lower end of said conduit arranged when open to permit the liquid to flow freely through the opening in the bottom of the outer cylinder, and means for discharging liquid between said cylinders. 110
75. 10. An apparatus of the class described, comprising an outer cylinder formed with an opening in its bottom, an inner cylinder open at its lower end to permit liquid to rise therein and separated from the outer cylinder to form a space between said cylinders, means for controlling the flow of the liquid upwardly in said inner cylinder or through the opening in the bottom of the outer cylinder, the said means comprising a conduit having an open upper end arranged within said inner cylinder and connected at its lower end with the opening in said outer cylinder and a valve mechanism at the lower end of said conduit arranged when open to permit the liquid to flow freely through the opening in the bottom of the outer cylinder, and means for discharging liquid between said cylinders. 115
80. 11. An apparatus of the class described, comprising an outer cylinder formed with an opening in its bottom, an inner cylinder open at its lower end to permit liquid to rise therein and separated from the outer cylinder to form a space between said cylinders, means for controlling the flow of the liquid upwardly in said inner cylinder or through the opening in the bottom of the outer cylinder, the said means comprising a conduit having an open upper end arranged within said inner cylinder and connected at its lower end with the opening in said outer cylinder and a valve mechanism at the lower end of said conduit arranged when open to permit the liquid to flow freely through the opening in the bottom of the outer cylinder, and means for discharging liquid between said cylinders. 120
85. 12. An apparatus of the class described, comprising an outer cylinder formed with an opening in its bottom, an inner cylinder open at its lower end to permit liquid to rise therein and separated from the outer cylinder to form a space between said cylinders, means for controlling the flow of the liquid upwardly in said inner cylinder or through the opening in the bottom of the outer cylinder, the said means comprising a conduit having an open upper end arranged within said inner cylinder and connected at its lower end with the opening in said outer cylinder and a valve mechanism at the lower end of said conduit arranged when open to permit the liquid to flow freely through the opening in the bottom of the outer cylinder, and means for discharging liquid between said cylinders. 125
90. 13. An apparatus of the class described, comprising an outer cylinder formed with an opening in its bottom, an inner cylinder open at its lower end to permit liquid to rise therein and separated from the outer cylinder to form a space between said cylinders, means for controlling the flow of the liquid upwardly in said inner cylinder or through the opening in the bottom of the outer cylinder, the said means comprising a conduit having an open upper end arranged within said inner cylinder and connected at its lower end with the opening in said outer cylinder and a valve mechanism at the lower end of said conduit arranged when open to permit the liquid to flow freely through the opening in the bottom of the outer cylinder, and means for discharging liquid between said cylinders. 130

ported in openings in the tops of said cylinder and casing for supporting the upper end of the conduit.

7. An apparatus of the class described, comprising a closed casing formed with a discharge opening in its bottom, a holder arranged within said casing and forming with the inner walls of said casing a relatively thin fluid space, the lower end of the holder being open to permit liquid to rise therein, a conduit arranged within said holder and connected at its lower end with the discharge opening in the bottom of the casing, the upper end of the conduit being open and arranged near the top of the holder, means for discharging material within the casing at a point above the open end of said conduit, and a rotary valve interposed between said conduit and said opening in the bottom of said casing.
- 10
- 15
- 20

8. An apparatus of the class described, comprising a closed casing formed with a discharge opening in its bottom, a holder arranged within said casing and forming with the inner walls of said casing a fluid space, the lower end of the holder being open to permit liquid to rise therein, a valve seat and valve therefor arranged in said opening and formed with axial openings through them, and also formed with ports adapted to register when the valve is rotated, a conduit arranged within said holder and connected at its lower end with said valve, and operating as a stem to rotate said valve, the upper end of the conduit being open and arranged near the top of the holder, means connected with the conduit and extending through the holder and casing to outside the latter for operating the conduit to rotate the valve, and means for discharging material within said casing at a point above the open end of said conduit.
- 25
- 30
- 35
- 40

9. An apparatus of the class described, comprising a casing having a top and a bottom, said bottom being formed with a discharge opening, a cylinder having a top and a bottom, devices for supporting the bottom of the cylinder above the bottom of the casing to form a fluid space between
- 45

them, means for discharging material on the top of said cylinder whereby it flows over said top and down between the walls of the casing and cylinder, the said cylinder being formed with an opening in its bottom and permitting the material to rise therein, a conduit arranged within said cylinder, the lower end of said conduit being connected with said discharge opening in the bottom of the casing and its upper end being open and permitting the material to overflow into said conduit and be discharged, and means for supporting the upper end of said conduit without obstructing the opening thereinto.

10. In an apparatus of the class described, the combination of two cylinders, one arranged within the other and the inner cylinder being separated from the outer one to form a circumferential space between them, a bottom for the outer cylinder, an annular bottom member for the inner cylinder, through which liquid passes, devices for supporting the annular bottom member in spaced relationship to the bottom of said outer cylinder to form a passageway through which the liquid flows from the circumferential space to the opening in the annular bottom member, the bottom of the outer cylinder being provided with an outlet, a conduit connected with the said outlet and extending upwardly within the inner cylinder, the upper end of the conduit being open to receive the liquid rising in said inner cylinder, a valve mechanism arranged at the lower end of said conduit and arranged when open to permit the liquid to flow directly from said outer cylinder through the outlet in the bottom thereof, and means for conveying liquid to the circumferential space between the two cylinders.

In testimony whereof I affix my signature, in the presence of two witnesses.
